COKE OVEN BATTERY

Heinrich Koppers, Essen, Germany, assignor, by
mesne assignments, to The Koppers Company
of Delaware, Pittsburgh, Pa., a corporation of
Delaware

Application May 14, 1931, Serial No. 537,311,
and in Germany May 14, 1930

9 Claims. (Cl. 202—143)

My invention relates to coke ovens for producing gas and coke and of the kind in which a large number of these ovens are combined to a battery, particularly those with transverse regenerators, that is, regenerators which are arranged in the direction of the oven chambers transverse to the longitudinal axis of the oven battery. Producer gas and air, or air only, are heated in these regenerators, whilst at other alternate periods, the checker brickwork of the regenerator is heated up by waste heat.

The invention has for its object certain improvements which eliminate the risk of producer gas passing over into the regenerators carrying waste heat or air, due to the formation of cracks in the supporting and separating brickwork of the regenerators.

According to the invention, this object is fulfilled by the provision of abutting-joints which traverse the entire oven battery in its vertical and longitudinal direction from the roof of the oven to the regenerator base. Supporting and separating walls separate the regenerator chambers from each other and are arranged transverse to the longitudinal direction of the oven battery. It is at the places in these walls which are liable to crack, that these abutting-joints are arranged according to the invention, so that the oven battery is therefore divided into several independent units in its transverse direction, each of these units being capable of expanding and contracting independently on the foundation plate.

Preferably the joints so divide up the oven battery that three approximately equal parts are produced, as experience has shown that with continuous brickwork, the greatest cracks occur at the limiting zones which correspond to such a subdivision.

A further object of the invention is the special arrangement and formation of the joints in the heating walls and in the regenerator-supporting and partition walls, the binders of the heating walls being preferably divided into two units by the joints.

In the accompanying drawing, forming a part of this specification and showing for purposes of exemplification a preferred form and manner in which the invention may be embodied and practiced, but without limiting the claimed invention specifically to such illustrative instance or instances:

Fig. 1 is a vertical section transverse through an oven battery, showing the improvement of the present invention in a section partly through the heating flues of a heating wall and partly

through an oven chamber and through the regenerators on line A—A of Fig. 2,

Fig. 2 is a vertical section along through a furnace battery on line II—II of Fig. 1,

Figs. 3 and 4 show the special arrangement of the joints according to the invention in horizontal sections through two different layers of bricks through a portion of a heating wall on lines III—III and IV—IV of Fig. 2.

Fig. 5 shows in the same way a horizontal section through a portion of a regenerator partition wall on line V—V of Fig. 2.

The oven battery shown in the drawing has a row of heating walls 1 which are arranged transverse to the oven battery and a number of oven chambers 2 between the heating walls 1. Underneath the heating walls 1, there is also a row of supporting walls 3 which carry the oven superstructure and are also arranged transverse to the battery. The heating walls 1 are provided with a series of vertical heating flues 4, which are furnished at the top with ports 5, all of which merge into a horizontal flue 6. The horizontal flue 6 of one heating wall is connected to the horizontal flue of the other heating wall by a series of communicating passages 7 which run through the roof 8 of the oven chambers 2. In the example shown in Fig. 1, six of these communicating passages are illustrated. Between the supporting walls 3 and parallel thereto, there are partition walls 9, forming a large number of regenerator spaces 11, 12, 13, 14, which in well known manner, are filled with checker brickwork 10 which in alternate succession is used for pre-heating the gas and air and for taking in the waste heat from the hot gases passing through it. Below these regenerator spaces are situated the bottom flues 15 which are connected to the respective regenerator chambers through the distributing grids 16, which are provided with openings 17. The heating flues 4 are also connected at the bottom in the usual manner with the respective generators, through the ducts 18 and 19.

The oven battery is cut in its entire longitudinal and vertical direction by abutting joints 20. In the example shown, two of these abutting joints are provided, so that in its transverse direction the oven battery is divided into three parts which work independently as far as the expansion and contraction of the material is concerned. The joints 20 are preferably taken through the binders or headers of the flues 4, as will be seen from Fig. 3. This arrangement effectively prevents a passage of combustion gases from the heating flues 4 into the distillation chambers 2, 110

it not being possible to arrange a horizontally staggered slotted system of joints in the heating walls 1, as is practicable in the relatively thick partition and supporting walls of the regenerators.

The header bricks 22, which are expanded hammer-shaped at one end 21 and constitute a portion of the layer of stretchers of the heating wall 1, are each divided into two headers 22a and 22b by the joints, the hammer-headed ends 21a and 21b of the headers 22 abutting each other in staggered formation as will be seen from Fig. 3. At the other end, the two headers 22a and 22b are bound in the stretchers, the headers 22b being staggered with respect to the joint of the abutting stretcher bricks 23 and 24.

In the next layer of bricks, the hammer-headed ends of the headers 22a and 22b form a part of the layer of stretchers of the other wall, as will be seen in Fig. 4. The slotted displacement of the joints in a horizontal direction is now so arranged that the joint runs through the entire brickwork in a perfectly vertical direction.

Fig. 5 shows the slotted staggered formation of the joints 21 in a horizontal direction through the supporting wall 3 of the regenerator. Of course, the joint also runs through the regenerator partition wall 9 in the same way.

In the oven base 25, which separates the oven chamber from the regenerator chambers, the joint is arranged staggered in a vertical direction. Thus leakages of gas from the regenerator chambers into the oven chambers are avoided.

In the oven roof 8, the joint 20, at about half the depth of the roof, runs out into a wider non-closing joint 26.

When the oven brickwork is erected, the joints 20 are built with such a gap that when expansion takes place during the working of the oven, the joints close up perfectly gas-tight. The separate parts of the oven battery thus formed by the abutting joints can expand and contract independently on the flat surface 27 of the foundation plate 28. In this way the movement of the brickwork during expanding and contracting, is taken up at the joints, so that cracking is avoided. This is very prone to occur in the regenerator separating brickwork in the type of oven described above, much to the detriment of its working, as the gas may leak from the particular regenerator 12 heating the producer gas to the other one 13 which is receiving heat at the time, and vice versa.

When the oven is heated up or put into operation, the entire brickwork may expand causing the joints to gap. When this occurs, or when there are leaky places in the joints from other causes, the trouble may easily be overcome by packing fine sand or the like into the joints, through the wide gap 26 in the oven roof 8. This sealing material fills up all leaky places and thus makes a gas-tight seal.

The invention as hereinabove set forth is embodied in a particular form of construction, but may be variously embodied within the scope of the claims hereinafter made.

I claim:

1. In a coke oven battery: a series of alternate coking chambers and heating walls therefor arranged side by side, each of said heating walls comprising vertical heating flues; regenerators communicating with said flues and arranged underneath the said series; said oven battery resting freely movable in horizontal direction on a fixed foundation plate; vertical expansion joints

running in the longitudinal direction of the oven battery and dividing the oven battery throughout its entire height and length except for the foundation plate.

2. In a coke oven battery: a series of alternate coking chambers and heating walls therefor arranged side by side, each of said heating walls comprising vertical heating flues; regenerators communicating with said flues and running transverse to the longitudinal axis of the oven battery and arranged under the said series; said oven battery resting freely movable in horizontal direction on a fixed foundation plate; vertical expansion joints running in the longitudinal direction of the oven battery and dividing the oven battery throughout its entire height and length except for the foundation plate.

3. In a coke oven battery: a series of alternate coking chambers and heating walls therefor arranged side by side, each of said heating walls comprising vertical heating flues; regenerators communicating with said flues and running transverse to the longitudinal axis of the oven battery and arranged under the said series; said oven battery resting freely movable in horizontal direction on a fixed foundation plate; vertical expansion joints running in the longitudinal direction of the oven battery and dividing the oven battery throughout its entire height and length except for the foundation plate.

4. In a coke oven battery: a series of alternate coking chambers and heating walls therefor arranged side by side, each of said heating walls comprising vertical heating flues; regenerators communicating with said flues and running transverse to the longitudinal axis of the oven battery and arranged under the said series; said oven battery resting freely movable in horizontal direction on a fixed foundation plate; vertical expansion joints running in the longitudinal direction of the oven battery and dividing the oven battery throughout its entire height and length except for the foundation plate; the said joints dividing the partition wall between two adjacent heating flues; the said partition wall between adjacent heating flues being formed of bricks enlarged into hammer-head shape at one end and so arranged that the hammer-head shaped enlargement forms a part of the wall of the coking chamber; the said hammer-head shaped bricks being horizontally divided in zig-zag formation at the place of the expansion joints, in such a way that the ends of the expansion joints lie in a vertical plane.

5. In a coke oven battery: a series of alternate coking chambers and heating walls therefor arranged side by side, each of said heating walls comprising vertical heating flues; regenerators communicating with said flues and arranged underneath the said series and running transverse to the longitudinal axis of the oven battery; said oven battery resting freely movable in horizontal direction on a fixed foundation plate; vertical expansion joints running in the longitudinal direction of the oven battery and dividing the oven battery throughout its entire length and height except for the foundation plate; the said joints dividing the partition wall between two adjacent heating flues; the said joints dividing the separating walls for the regenerators and running in zigzag formation in horizontal direction within these last mentioned walls.

6. In a coke oven battery: a series of alternate coking chambers and heating walls therefor arranged side by side, each of said heating walls comprising vertical heating flues; regenerators 5 communicating with said flues and running parallel to the longitudinal axis of the oven battery and arranged underneath the said series; said oven battery resting freely movable in horizontal direction on a fixed foundation plate; vertical 10 expansion joints running in the longitudinal direction of the oven battery and dividing the oven battery throughout its entire height and length except for the foundation plate; the said joint dividing the roof of the regenerators and running 15 in vertical direction in zigzag formation within this roof.
7. In a coke oven battery: a series of alternate coking chambers and heating walls therefor arranged side by side, each of said heating walls comprising vertical heating flues; regenerators 20 communicating with said flues and arranged underneath the said series; said oven battery resting freely movable in horizontal direction on a fixed foundation plate; vertical expansion joints running in the longitudinal direction of the oven battery and dividing the oven battery throughout their entire height.
8. In a coke oven: a series of alternate coking chambers and heating walls therefor arranged side by side, each of said heating walls comprising combustion flues; regenerators communicating with said flues and arranged underneath said series; vertical expansion joints running in the longitudinal direction of the oven battery and dividing the oven battery throughout its entire height.
9. In a coke oven: a series of alternate coking chambers and heating walls therefor arranged side by side, each of said heating walls comprising combustion flues; regenerators communicating with said flues and arranged underneath said series; vertical expansion joints running in the longitudinal direction of the oven battery and dividing the oven battery throughout its entire height.
